United States Patent Office

Des. 227,340
Patented June 19, 1973

227,340

ELECTRICAL KEY

Robert B. Phinizy, Yorba Linda, Calif., assignor to
Eaton Corporation, Cleveland, Ohio

Filed Oct. 4, 1971, Ser. No. 186,371

Term of patent 14 years

Int. Cl. D8—07

U.S. Cl. D8—136

FIG. 1 is a front elevational view of an electrical key showing my new design;

FIG. 2 shows a top plan view thereof;

FIG. 3 shows a left hand end view of the key shown in FIG. 1;

FIG. 4 shows a right hand end view;

FIG. 5 shows a rear elevational view thereof; and

FIG. 6 is a bottom view thereof.

I claim:

The ornamental design for an electrical key, substantially as shown.
